DESULFURIZATION OF OLEFINIC NAPHTHA

Robert C. Arnold, Chicago Heights, Ill., and John F. Deters, Valparaiso, Ind., assignors to Standard Oil Company, Chicago, Ill., a corporation of Indiana

Application November 29, 1949, Serial No. 129,902.

4 Claims. (Cl. 196—24)

1

This invention relates to an improved method of desulfurizing highly olefinic naphthas and it pertains more particularly to the desulfurization of coke still naphtha by extraction with dimethylsulfolane containing less than 15 per cent of water, the extract being hydrodesulfurized for blending with the raffinate.

An object of the invention is to provide an improved method and means for removing sulfur compounds from highly olefinic naphthas without materially altering the olefin to paraffin ratios and without suffering large treating losses. A particular object is to desulfurize a naphtha in which the olefinic content substantially equals or exceeds the paraffinic content, an outstanding example of such naphtha being coke still naphtha. A further object of the invention is to convert a high sulfur olefinic naphtha into low sulfur olefinic gasoline of a high anti-knock value with minimum treating losses and with a minimum amount of olefins subjected to hydrofining when that process is employed for converting sulfur compounds to H₂S for facilitating their removal from extract material.

We have discovered that when 2,4-dimethylsulfolane is employed for extracting a highly olefinic naphtha, such as coke still naphtha, the solvent does not effect separation between olefins and paraffins (as would be expected from U. S. 2,360,861), but on the contrary produces remarkably high raffinate yields of substantially the same olefin to paraffin ratio as the initial charging stock but with a remarkably decreased amount of sulfur and aromatic components. The selectivity of 2,4-dimethylsulfolane for sulfur removal is unexpectedly much higher in the case of such highly unsaturated low boiling charging stock than in the case of saturated charging stocks or charging stocks of higher boiling range.

The accompanying drawing schematically illustrates a flow diagram of a system for practicing the invention.

The invention is applicable to high sulfur olefinic naphthas generally, i. e. to naphthas in which the olefin to paraffin ratio is in the range of about 3:1 to 1:3 and is particularly advantageous for charging stocks in which the olefinic content exceeds the paraffinic content. By "high sulfur," we mean a sulfur content which is at least about .25 per cent and which is usually in the range of about .5 to 1 per cent or more. By "naphtha," we mean a normally liquid hydrocarbon fraction boiling below 450° F. and usually boiling almost entirely within the range of 100°

2

to 400° F. An outstanding example of a high sulfur olefinic naphtha is the naphtha produced by the coking of high sulfur reduced crude in any known manner such, for example, as by continuously introducing heated charging stock into a coke drum at about atmospheric pressure to 50 pounds per square inch at a temperature in the range of about 850 to 950° F., and continuing the operation until coke solidifies in the drum, the vaporous products from the drum being fractionated into a coke still naphtha fraction and one or more heavier fractions. While the invention may be applicable to high sulfur olefinic naphthas produced by thermal cracking or by catalytic cracking, its outstanding advantage is in the refining of coke still naphtha because this particular high sulfur olefinic naphtha is the most difficult of all to desulfurize or otherwise refine by conventional methods.

20 Coke still naphtha has an olefin to paraffin ratio of approximately 2:1, and contains from about .25 to 4 per cent sulfur by weight, a representative stream containing for example about 1 per cent sulfur. The bromine number of the olefinic components of a representative coke still naphtha may be about 70 to 85 but there is a bromine absorption due to sulfur corresponding to about 5 bromine numbers per weight per cent sulfur. A correlation of bromine numbers and sulfur content in original charge, raffinate and extract, respectively, can thus be employed to determine the extent to which olefins are selectively removed from paraffins in an extraction process.

25 Our extractant is 2,4-dimethylsulfolane which boils at about 281° C. and which thus may be readily separated from naphtha raffinates and extracts by simple distillation. For optimum results, the dimethylsulfolane should contain a small amount of water which should be less than 10 per cent and usually in the range of about 1 to 5 per cent or approximately 2 per cent when the solvent to oil ratio is of the order of 1:1; with higher solvent to oil ratios, the water content may be as high as 15 per cent. The water is most effectively utilized when introduced into the extract portion of a countercurrent extraction system. Thus, when a countercurrent tower extractor is employed, a small amount of the water may be introduced with the solvent at the top of the tower, but the water is most effectively utilized when introduced into the extract phase near the point of charging stock inlet or between this point and the bottom of the tower. 30 The invention is not limited to tower type ex-

traction, however, and the extraction may be effected batchwise, in a multiple batch system, in a countercurrent batch system, or by any other extraction method known to those skilled in the art.

The extraction can best be carried out with a solvent to charging stock volume ratio in the range of .3:1 to 3:1, the preferred range being about .5:1 to 1:1. The extraction may be effected at ordinary room temperature or within the range of about 0° C. to 40° C. The pressure should be such as to keep all material in liquid phase.

As a specific example of the invention, the following data were obtained when a coke still naphtha of about 80 bromine number containing .9 weight per cent sulfur was extracted at room temperature with a 1:1 solvent ratio with 2,4-dimethylsulfolane having the indicated water content. These results were obtained in the single batch extraction.

Percent Water in Solvent	Percent Raffinate Recovered	Percent Sulfur in Raffinate	Percent Desulfurization	Desulfurization ¹ Selectivity
0.....	70	.46	49	1.6
2.....	76	.47	48	2.0
5.....	82	.50	45	2.5

¹ Percent desulfurization divided by treating loss.

In another example of our invention, portions of the same charging stock were countercurrently extracted in a column at room temperature at a 1:1 solvent ratio (the water being introduced at the top of the column where water was used) and the following data were obtained:

Percent Water in Solvent	Percent Raffinate Recovered	Percent Sulfur in Raffinate	Percent Desulfurization	Desulfurization ¹ Selectivity
0.....	62	.17	81	2.1
2.....	70	.25	72	2.4

¹ Percent desulfurization divided by treating loss.

It should be understood that increased concentrations of water may be used in either of the above examples in order to obtain higher raffinate yields, but in so doing, somewhat lower desulfurization will result.

A surprising result is that the extraction of the high sulfur olefinic naphtha does not produce any appreciable change in the paraffin to olefin ratio. The charge in the countercurrent extraction example hereinabove set forth had a bromine number of about 80, the raffinate a bromine number of about 75, and the extract a bromine number of about 91. Since one weight per cent sulfur in organic sulfur products is equivalent to 5 bromine numbers, the bromine number of the feed may be broken down to a bromine absorption by olefins corresponding to about 75 and a bromine absorption due to sulfur corresponding to about 5. Since the raffinate contained .25 weight per cent sulfur, a like break down indicates a 74 bromine number for the olefin content thereof. The extract, on the other hand, contained about 2.5 weight per cent sulfur so that the olefin content thereof apparently had a bromine number of about 78. These data show that there is no appreciable separation of olefins from paraffins, i. e. no appreciable selectivity of 2,4-dimethylsulfolane for olefines when the solvent is employed for extracting a high sulfur olefinic naphtha.

It should be pointed out that since the olefinic

5 naphtha, raffinate and extract are lower boiling than the solvent, separation of the solvent may be effected by simple distillation, although any final traces of solvent may be removed by water scrubbing if desired. An important feature of 10 dimethylsulfolane in extracting high sulfur olefinic naphtha is the fact that the solvent does not cause any condensation, polymerization or alkylation and does not combine with the olefins (as is the case, for example, with hydrogen fluoride and certain other solvents).

The sulfur contents of the raffinates produced by our invention are sufficiently low so that they 15 may be blended in finished gasoline to meet stringent sulfur specifications. The extract which only constitutes a small fraction of the original charging stock, but which contains most of the sulfur compounds, may be hydrodesulfurized by any known process, such, for example, as hydro-forming, hydrofining, autofining, etc. The catalysts employed for this step may be an eighth group metal or metal sulfide as described in U. S. 2,273,297, but it is preferably a supported sixth group metal compound, such as chromium or molybdenum oxide on alumina as employed in hydroforming (note U. S. 2,388,536) or supported cobalt molybdate as used in hydrofining (note Ind. Eng. Chem., vol. 35, pages 1160 to 1167), or tungsten nickel sulfide as described in the paper 20 presented by Eagle and Rudy entitled "Application of Cyclic Adsorption Process to Desulfurization of Cracked Naphtha" before the American Chemical Society in September 1949. Autofining is similar to hydrofining except that the hydrogen is supplied by naphthenes added to the charging stock. Since these hydrodesulfurization processes are well known to those skilled in the art (product yields and product qualities, both alone and blended with initially separated components being likewise known, as described for example in the Eagle and Rudy paper), it is unnecessary 25 to describe the hydrodesulfurization or the yields and properties of finished motor fuel in further detail.

An important feature of our invention is the 30 remarkable effectiveness of dimethylsulfolane for removing from a high sulfur olefinic naphtha an extract which contains such a larger proportion of the original sulfur but so small a proportion of the original olefins. Thus, if the per cent sulfur divided by the corrected bromine number of the high sulfur olefinic naphtha, raffinate and extract respectively are compared, it will be found 35 that this measure of sulfur to olefin ratio is 0.012 with the original high sulfur olefinic naphtha, 0.003 in the case of the raffinate and 0.03 in the case of the extract, the ratio in the case of the extract being ten times that in the case of the raffinate and about three times that in the case of original charge.

Our invention provides an enormously simpler and less expensive method of treating a high sulfur olefinic naphtha for obtaining a relatively small amount of extract of high sulfur and low olefin content than was heretofore known to the art. Since only the extract requires hydrodesulfurization and the raffinate (which contains most of the olefins) is not subjected to hydrodesulfurization, we minimize hydrodesulfurization expense and avoid saturation of any olefins separated as raffinate. We thus not only obtain 40 higher yields of a finished product blend, but we obtain a finished product blend of remarkably high octane number and at a relatively low cost.

Since any water employed in our extraction

step is separated along with the raffinate and extract respectively while they are being distilled in the solvent recovery steps, the water may be separated from the distilled and condensed raffinate and extract respectively by simply settling condensed water from the oily layer and returning the settled water for example to an intermediate or low point in the extract tower. This provides a much simpler and less expensive operating procedure than processes wherein water distills with solvent from extract and raffinate and cannot be separated from condensed solvent by simple settling.

Referring to the drawing, the high sulfur olefinic naphtha charge is introduced by line 10 to extraction tower 11 into which dimethylsulfolane is introduced through line 12 and a small amount of water is introduced through line 13 and/or 14. Raffinate is introduced by line 15 to still 16 from which hydrocarbons and water are taken overhead through condenser 17 to separator-receiver 18, the oil from said receiver being withdrawn through line 19 for final blending, and the water being returned by line 20 to line 13 and/or 14. Extract is introduced by line 21 to still 22 from which oil and water vapors are condensed in cooler 23 and introduced into separator 24, separated water being returned by line 25 to line 13 and/or 14. Solvent is returned from still 16 by line 26 and from still 22 by line 27, said solvent being heat exchanged in exchangers 28 and 29, respectively, and then cooled in cooler 30. Extract is withdrawn from settler 24 through line 31, is hydrodesulfurized in system 32 for removing sulfur as H_2S and the desulfurized product is withdrawn through line 33 for blending with raffinate from line 19 to give the final low sulfur, olefinic gasoline.

While our invention has been described with respect to specific operating examples, it should be understood that alternative operating conditions and modifications will be apparent to those skilled in the art from the above description. Other alkyl sulfolanes, which are substantially equivalent in extraction properties to 2,4-dimethylsulfolane, may be employed instead of 2,4-dimethylsulfolane itself.

We claim:

1. The method of obtaining a low sulfur olefinic gasoline of high anti-knock value from a high sulfur olefinic naphtha which comprises extracting a naphtha having an olefin to paraffin ratio in the range of 3:1 to 1:3 and containing more than .25 per cent sulfur with 2,4-dimethylsulfolane under conditions to form an extract phase containing most of the sulfur and a raffinate phase containing most of the olefins, employing with the 2,4-dimethylsulfolane in the extraction step an amount of water in the range of from about 1 to 5 percent by volume based on total solvent, separately removing solvent and water from each of said phases, hydrodesulfurizing the solvent-free extract phase to eliminate sulfur therefrom and blending the hydrodesulfurized extract with the solvent-free raffinate to form an olefinic low sulfur gasoline of high anti-knock value.

2. The method of obtaining a low sulfur olefinic gasoline of high anti-knock value from a high sulfur olefinic naphtha which comprises extracting a naphtha having an olefin to paraffin ratio in the range of 3:1 to 1:3 and containing more than .25 per cent sulfur with 2,4-dimethylsulfolane under conditions to form an extract phase containing most of the sulfur and a raffinate phase containing most of the olefins, employing with the 2,4-dimethylsulfolane in the extraction step an amount of water in the range of from about 1 to 5 percent by volume based on total solvent, separately removing solvent from each of said phases by distillation under conditions to distill water with the raffinate and extract respectively, separately condensing distilled raffinate and extract along with any water contained therein to form condensates, settling water from at least one of said condensates and returning said separated water to the extracting step.

3. The method of claim 2 which includes the further steps of hydrodesulfurizing the solvent-free extract to eliminate sulfur therefrom and blending the hydrodesulfurized extract with the solvent-free raffinate.

4. The method of converting a coke still naphtha having an olefinic content greater than its paraffinic content and having a sulfur content in the range of .25 to 4 percent into an olefinic gasoline of low sulfur content and high anti-knock value, which method comprises countercurrently contacting said coke still naphtha with 2,4-dimethylsulfolane in an extraction zone, introducing an amount of water in the range of about 1 to 5 percent by volume based on total 2,4-dimethylsulfolane into the extract end of said extraction zone, introducing an extract phase from the extraction zone to a first distillation zone, distilling extract and water from 2,4-dimethylsulfolane in the first distillation zone, condensing vapors from said first distillation zone and separating water condensate from the extract, recycling said water condensate to the extract end of said extraction zone, introducing raffinate phase from said extraction zone to a second distillation zone, distilling raffinate from 2,4-dimethylsulfolane in said second distillation zone, returning undistilled 2,4-dimethylsulfolane from the base of both distillation zones to the raffinate end of the extraction zone, hydrodesulfurizing the extract and blending the hydrodesulfurized extract with said raffinate to obtain said low sulfur olefinic gasoline of high anti-knock value.
